His Attorney.

UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

CONDENSER APPARATUS.

1,394,929.

Specification of Letters Patent. Patented Oct. 25, 1921.

Application filed October 8, 1919. Serial No. 329,379.

To all whom it may concern:

Be it known that I, SANFORD A. Moss, a citizen of the United States, residing at Lynn, in the county of Essex, State of Massachusetts, have invented certain new and useful Improvements in Condenser Apparatus, of which the following is a specification.

The present invention relates to condenser systems such as are used in connection with elastic fluid turbines, for example, and particularly to such systems which comprise a surface condenser, a liquid pump for withdrawing condensate therefrom, and an ejector pump for withdrawing air and uncon-
10 densed vapors therefrom.

The object of my invention is to provide an improved arrangement in such a system and for a consideration of what I believe 0 to be novel and my invention, attention is directed to the accompanying description and the claims appended thereto.

In the drawing, the figure is a diagrammatic view of a system embodying my in-
5 vention.

Referring to the drawing, 5 indicates a usual type of surface condenser having heads 6 and 7 connected by tubes 8 through which the cooling water is conveyed. 9 indicates a conduit for conveying cooling water to the condenser and 10 a conduit for conveying it away therefrom. The elastic fluid to be condensed (which may be exhaust steam from a turbine for example) enters the condenser through conduit 11 and the condensate runs out through opening 12. 13 indicates a conduit through which the air and uncondensed vapors are removed. Connected with conduit 13 is an ejector pump comprising two stages—a first stage comprising the ejector 14 and a second stage comprising two ejectors 15 and 16, connected in parallel to each other and in series to the first stage ejector 14. Condensable elastic fluid for actuating ejectors 14, 15 and 16 is supplied thereto through pipes 17, 18 and 19 all of which may be connected to a supply pipe 20 leading from any suitable source. Ordinarily, in the case of a steam turbine, steam is used as the actuating fluid and under such circumstances the pipe 20 may lead from the same boiler which supplies steam to the turbine. In pipes 17, 18 and 19 are suitable valves 21, 22 and 23 for con-
trolling the flow of actuating fluid to the re-
spective ejectors. The suction inlet of ejector 14 is connected to conduit 13 by a pipe 24 in which is a suitable valve 25. The discharge pipe or mixing tube of ejector 14 is connected by a conduit 26 to the casing of an intercooler or condenser 27. 28 is a valve by means of which the discharge conduit of
ejector 14 may be shut off.

Leading from the casing of condenser 27 is a conduit 29 to which the suction inlets 55 of ejectors 15 and 16 are connected by conduits 30 and 31 in which are suitable valves 32 and 33 respectively. The discharge conduits or mixing tubes of ejectors 15 and 16 are connected in parallel to discharge pipe 34 which leads to a hot well 35. The end 60 of discharge pipe 34 terminates beneath the level of the liquid in the hot well 35. 36 is a suitable pump for withdrawing liquid from the hot well and delivering it to the 65 boiler or boilers which may be the ones which supply steam to the system. Condenser or intercooler 27 is of the spray type and comprises an upper chamber 37 sepa-
rated from a lower chamber 38 by a partition wall 39 in which are suitable openings 40 through which liquid is sprayed. Fastened to and located beneath condenser 5 is a well 41 which receives the condensate 70 discharged through opening 12, and connecting well 41 to chamber 37 of condenser 27 is a length of pipe 42 in which is a suitable valve 43. It will thus be seen that the condensate from well 41 is fed by gravity 75 through pipe 42 to condenser 27 where it serves as a cooling liquid for such condenser. Pipes 26 and 29 connect with chamber 38 of condenser 27 and the lower side of such chamber is connected by a length of pipe 44 to a suitable pump 45 here shown as being 80 a centrifugal pump. In pipe 44 is a valve 46. Pump 45 is what is ordinarily termed a condensate pump and has its discharge conduit 47 connected to hot well 35. Connecting well 41 to pipe 44 beyond valve 46 is 85 an overflow pipe 48 which serves to convey liquid directly from well 41 to the inlet of pump 45 after a predetermined high level is reached in well 41. Leading into well 41 is a supply pipe 49 at the end of which is a 90 valve 50 controlled by a float 51. Pipe 49 may lead from any suitable source of liquid supply. The arrangement is such that when
100
105

the liquid in well 41 reaches a predetermined low level, float 51 will lower sufficiently to open valve 50 and admit liquid to well 41. On the other hand, when the liquid in well 41 is above a predetermined level, float 51 will maintain valve 50 closed. Connecting discharge conduit 13 to conduit 26 is a bypass conduit 52 in which is a valve 53. When valve 53 is open it will be seen that 10 ejector 14 is by-passed and ejectors 15 and 16 are then connected directly to conduit 13. 54 is a liquid level gage glass for indicating the level of liquid in pipe 44.

In normal operation by-pass valve 53 is 15 closed and ejector 14 and either ejector 15 or 16 or both of them are active. Condensable elastic pumping fluid being admitted to them through pipes 17, 18 and 19. Ejector 14 pumps air and uncondensed vapors from 20 condenser 5 and the condensable elastic pumping fluid, air and vapors discharged from it pass through conduit 26 to chamber 38 of condenser 27. In passing through chamber 38 they come in contact with the 25 streams of liquid issuing from openings 40 in plate 39 the result being that the condensable elastic fluid is condensed completely or in part, and that the condensate is carried along with the liquid through 30 pipe 44 to the suction side of pump 45, the elastic fluid giving up heat to the liquid. The air and uncondensed vapors are then drawn from chamber 38 through pipe 29 by 35 the second stage of the ejector pump and are delivered by it along with elastic pumping fluid used in such ejectors through pipe 34 to the hot well 35. Here they issue from the end of pipe 35 beneath the level of the liquid therein with the result that the 40 condensable vapors are condensed giving up their heat to such liquid while the air and uncondensed vapors bubble out through the liquid. By this means it will be seen that all the heat contained in the motive fluid discharged 45 from the ejectors is recovered being put into the liquid in the hot well, which liquid is used to feed the boilers.

Condenser or intercooler 27 is placed a distance below condenser 5 such that a liquid head will be established in pipe 42 sufficiently great to force liquid by gravity through condenser 27. This means of course that the liquid head be great enough to overcome the difference in pressure which 50 exists between the suction side and the discharge side of ejector 14. Likewise pipe 44 is made sufficiently long to provide a suitable liquid column for feeding the liquid from intercooler 27 to pump 45. Overflow pipe 48 is of such length that a column 55 of liquid will be established in it, as shown, to seal it.

With the arrangement disclosed, I preferably employ two ejectors in parallel as 60 the second stage of the ejector pump since

by so doing I am enabled to adapt the ejector for either heavy load or light load. It will be understood that by "heavy load" I mean when it is necessary that a considerable amount of air and uncondensed vapors are required to be pumped in order to maintain a given vacuum, while by "light load" I mean where a comparatively lesser amount of air and uncondensed vapors are required to be pumped in order to maintain the desired vacuum. The latter condition exists, of course, when there is but little leakage of air to the condenser system, *i. e.*, when the condenser system is tight. Under such circumstances, I find 70 that I can maintain ample vacuum by using only one of the ejectors 15 or 16, thereby materially economizing the use of the actuating fluid. Also in case for any reason, it is desired or found necessary to not 75 use the first stage ejector 14, then the same can be cut off by closing valves 25 and 28 and the second stage of the pump connected directly to the condenser by way of pipe 52, the by pass valve 53 being open. 80 By then using the two ejectors 15 and 16 in parallel, I can, with the single stage, obtain a fair vacuum for operation.

With the above described arrangement it 85 will be seen that I utilize the condensate 90 from the main condenser as cooling liquid for the intercooler of the multi-stage ejector pump thereby putting the heat of the fluid discharged from the first stage ejector into such liquid. Also it will be noted 95 that by placing the intercooler below condenser 5 by the necessary amount, the condensate flows through it by gravity thereby 100 eliminating the necessity of using a pump. Furthermore, by providing an overflow pipe 105 48 and an auxiliary supply pipe 49, I make the system entirely automatic providing against both an oversupply and an undersupply of condensate. I thus obtain a complete system which is simple in arrangement and efficient in operation.

In accordance with the provisions of the patent statutes, I have described the principle of operation of my invention, together 115 with the apparatus which I now consider to represent the best embodiment thereof, but I desire to have it understood that the apparatus shown is only illustrative and that the invention may be carried out by other means.

What I claim as new, and desire to secure by Letters Patent of the United States, is:

1. In combination, a condenser, a multi-stage ejector pump connected therewith, an intercooler for said pump, said intercooler 120 being located below said condenser, a conduit for conveying condensate from said condenser to said intercooler, said conduit being of such length that liquid will flow by gravity from the condenser through the in- 125 130

tercooler, and automatic means for supplying liquid to said intercooler in case the condensate supply is insufficient.

2. In combination, a condenser, a multi-stage ejector pump connected therewith, an intercooler for said pump, said intercooler being located below said condenser, a conduit for conveying condensate by gravity from said condenser to said intercooler, and a drain pipe for conveying away any condensate in excess of that required by said intercooler.

3. In combination, a condenser, a multi-stage ejector pump connected therewith, an intercooler between stages of said pump, said intercooler being located below said condenser, a conduit connecting the condenser to the intercooler, said conduit being of such length that the intercooler is located a distance below said condenser such that a head is established which provides a pressure sufficiently great to force liquid by gravity through said intercooler.

4. In combination, a condenser, a multi-stage ejector pump connected therewith, an intercooler for said pump, said intercooler being located below said condenser, a conduit for conveying condensate by gravity from said condenser to said intercooler, automatic means for supplying liquid to said intercooler in case the condensate supply is insufficient, and a drain pipe for conveying away any condensate in excess of that required by the intercooler.

5. In combination, a condenser, a multi-stage ejector pump connected therewith, an intercooler for said pump, said intercooler being located below said condenser, a conduit for conveying condensate from said condenser to said intercooler where it is utilized as cooling liquid, said intercooler

being located a sufficient distance below the condenser that liquid will flow by gravity from the condenser through the intercooler, a hot well, and means for conveying the cooling liquid from said intercooler to the hot well.

6. In combination, a condenser, a multi-stage ejector pump connected therewith, an intercooler for said pump, said intercooler being located below said condenser, a conduit for conveying condensate from said condenser to said intercooler where it is utilized as cooling liquid, said intercooler being located a sufficient distance below the condenser that liquid will flow by gravity from the condenser through the intercooler, a hot well, means for conveying the cooling liquid from said intercooler to the hot well and conduit means for conveying the discharge from the last stage of said ejector pump to the hot well.

7. In combination, a condenser, a multi-stage ejector pump connected therewith comprising a first stage consisting of a single ejector and a second stage consisting of a plurality of ejectors connected in parallel to each other and in series with said first stage, an intercooler between said first and second stages, said intercooler being located at a lower level than said condenser and utilizing condensate from said condenser as cooling liquid, said intercooler being located below the condenser a distance such that a head is established which provides a pressure sufficiently great to force liquid by gravity through said intercooler, and means whereby either or all of said second stage ejectors may be used.

In witness whereof I have hereunto set my hand this third day of October, 1919.

SANFORD A. MOSS.
